UNITED STATES PATENT OFFICE.

RALPH C. STIEFEL, OF ELLWOOD CITY, PENNSYLVANIA.

METHOD OF FORMING BLANKS FOR MAKING SEAMLESS TUBES.

Application filed November 8, 1927. Serial No. 231,906.

The invention relates to the manufacture of seamless tubing, and has particularly to do with the preparation of blanks for use in such manufacture.

5 The usual method of forming a blank for the manufacture of seamless tubing by plug rolling or other processes is to pierce and materially lengthen a solid billet by revolving it between obliquely-disposed barrel-shaped rolls and force it over a mandrel held against longitudinal movement but mounted for rotation with the billet. In some cases, particularly in the manufacture of larger sized tubing, the thus pierced billet 10 is passed through a second pair of obliquely-disposed barrel-shaped rolls and over a larger mandrel to further lengthen the billet, enlarge its diameter, and reduce its wall thickness.

15 20 The barrel-shaped piercing rolls form a converging entering pass and a diverging exit pass, and accordingly have their highest peripheral speeds at the narrowest point of the pass where the billet is reduced to its smallest diameter. Therefore, the billet is acted upon at different transverse sections by peripheral roll speeds which are inversely in proportion to the angular surface speed of the billet. This condition is very severe 25 30 on the metal, producing severe distortions of it and greatly aggravating or developing defects in the billet which cause loss of material and increase the labor and other cost of production.

35 These prejudicial consequences are greatly magnified in the piercing operation, or operations, when a second piercing pass is used, by reason of the fact that the billets while being pierced have been materially elongated, particularly in the diverging portion 40 of the pass where the pierced billet passes over the enlarged tapered mandrel. The piercing action may be compared to that of a continuous rolling mill in which each successive pair of rolls forms a work pass. When a billet is being pierced each of its 45 diametrical lines comes under compression a number of times similar to the successive compressions effected by succeeding pairs of rolls in a continuous mill. However, in a continuous mill the successive roll passes are formed to properly take care of the volume or section of a work piece or blank in order to eliminate stresses on the blank between 50 the passes; whereas in a piercing mill in

which a billet is materially elongated in the entire pass, and also in which the diameter of the pierced portion of the billet is enlarged and its wall thickness diminished, excessive stresses are imposed upon the metal, 60 which stresses greatly magnify those necessarily inherent in a piercing operation by reason of the inversely varying roll speeds previously explained. Furthermore, these conditions of piercing result in an excessive 65 consumption of power, and in a corresponding increase in operating expense.

It is well known that billets used for piercing must be of superior quality to withstand the punishment to which the metal is 70 subjected by reason of the severe stresses imposed upon them. When losses occur, that is to say, when defective tubing is produced, a chaotic condition arises, the operating management of the tube mill, believing that working conditions have been maintained constant and proper, attributes the losses to defective metal, and the steel manufacturer, believing that the metal is not defective, attributes the losses to improper conditions in the piercing procedure. Manifestly it is desirable to eliminate one of the causes of defective tubing so that the source of trouble may be determined.

The object of this invention is to provide 85 a method of forming a blank for making a seamless tube whereby the stresses imposed on the metal are reduced to a minimum, and as a result thereof the power consumption lessened, the labor cost diminished, the scrap 90 losses reduced, and the cause of scrap losses readily determined.

In the practice of the invention, a blank for making a seamless tube is formed by progressively piercing a solid billet in such a manner as to effect a minimum elongation of it. Rather than commencing with a relatively short and thick billet, as is the prevailing practice, I use a billet of relatively increased length and diminished diameter, and elongate it only in the converging portion of a pass between piercing rolls, and there only to the extent necessary to cause sufficient grip upon the billet by the rolls to force the billet over the point of a piercing mandrel. In the diverging portion of the roll pass the cross sectional area of the then pierced portion of the billet is maintained constant, so that the diameter of the billet is increased 100 and its wall thickness diminished without 105 110

imposing upon the metal the excessive stresses heretofore existing incident to the elongation of the billet in this portion of the pass. When the pierced billet is again 5 passed through a piercing mill to further enlarge its diameter and diminish its wall thickness, this is done with little, if any, elongation of the billet in any portion of the pass, and with consequent elimination of 10 severe stressing of the metal.

The invention will be further explained with reference to the accompanying drawings, of which Fig. 1 is a view of a pair of barrel-shaped piercing rolls, showing a solid 15 billet in the process of being pierced; Fig. 2 a view of a pair of mushroom-shaped rolls showing a pierced billet in the process of having its diameter increased and its wall thickness diminished; Fig. 3 a side view of 20 a solid billet of such relative proportions as may advantageously be used in the practice of the invention; Fig. 4 a longitudinal central sectional view of the billet of Fig. 3 after having been pierced by the mill of Fig. 1; 25 and Fig. 5 a longitudinal central sectional view of the billet of Fig. 4 after having passed through the mill of Fig. 2.

The piercing mill of Fig. 1 comprises a pair of barrel-shaped obliquely-disposed 30 rolls 1 which, with a mandrel 2 arranged between them, form a piercing pass. A solid billet 3, such as shown in Fig. 3, enters the left end of the roll pass and leaves its right end in the form of a pierced billet 4, 35 such as illustrated in Fig. 4. The piercing pass has two portions, a converging portion extending from the plane of points 5 where the solid billet is engaged by the rolls to the plane of points 6 where the rolls are of 40 greatest diameter, and a diverging portion extending from the plane of points 6 to the plane of points 7 where the pierced billet passes beyond the mandrel. In practice the taper of the rolls to form the converging pass 45 is only of such angularity as is necessary to produce enough grip between the rolls and the billet to force the billet forwardly onto the point of the mandrel which customarily extends into the converging portion of the 50 pass. This convergence necessarily produces some elongation of the billet, but throughout the major portion of the converging section of the pass the billet is solid and therefore elongation stresses do not so severely 55 stress or punish the metal.

In the diverging pass, the piercing rolls 1 and the mandrel 2 are so formed or tapered and adjusted that there is little, if any, elongation of the pierced billet. Such being the 60 case, the cross sectional area of the pierced portion of the billet remains uniform in all transverse planes from that passing through the points 6 to that passing through the points 7 at the end of the pass, or in other 65 words, in all transverse planes in the diverg-

ing portion of the pass. Also, considering the pierced portion of the billet in the pass as extending from the transverse plane through the point of the mandrel to the transverse plane through the points 7, the 70 cross sectional area of the major part of the pierced portion of the billet is maintained uniform during the expanding and reducing operation. Thus the billet is pierced with a minimum attending elongation, and with 75 little, if any, elongation in the diverging portion of the piercing pass where elongation stresses are severest on the metal.

When, in the practice of this invention, the pierced billet 4 of Fig. 4 is acted upon 80 to enlarge its diameter and diminish its wall thickness, it is preferably passed through a piercing mill of the type indicated in Fig. 2 as comprising a pair of mushroom-type rolls 10 and a mandrel 11 arranged between them, although if desired barrel-shaped piercing rolls may be used. By using mushroom-type rather than barrel-shaped rolls, the peripheral speeds of the rolls at their various points in the diverging portion 85 of the piercing pass corresponds in general to the angular speed of rotation of the pierced billet at the various points that work is applied to it to enlarge its diameter and reduce its wall thickness. As in the 90 case of the mill of Fig. 1, the pass formed by the rolls 10 also has a converging and a diverging portion, but in neither of these portions is the pierced billet elongated. In 95 the converging portion of the pass, extending from the plane of the points 12 to the plane of the points 13, the billet is gripped and pressed inwardly upon the head of mandrel 11, but its wall thickness is not there 100 reduced and the metal is only slightly 105 worked. When in the diverging portion of the pass, extending from the plane of the points 13 to that of the points 14, the diameter of the billet is enlarged and its wall thickness diminished with effecting little, if 110 any, elongation. Accordingly, throughout the entire pass the cross sectional area of 115 the pierced billet remains uniform.

The solid billet 3 shown in Fig. 3, the pierced billet of Fig. 4, and the expanded 120 billet 15 of Fig. 5 typically represent a blank-forming procedure capable of being carried out in the practice of this invention. The ratio of the length to the diameter of solid billet 3 is greater than that used in the 125 customary practice, and the percentage increase in length of this billet to produce the pierced billet 4 is less than in the customary practice. Furthermore, the expanded billet 15 of Fig. 5 is of the same, or 130 substantially the same, length as the pierced billet 4. These views therefore show how, in the preparation of a blank according to this invention, the blank is given a minimum elongation with an attendant diminution in 135

working stresses placed upon the blank. By thus diminishing the stresses, much less power is required, scrap losses are materially reduced, one of the causes of defective tubing is greatly reduced if not entirely eliminated, and the labor and other cost of manufacture of tubing is materially reduced.

According to the provisions of the patent statutes, I have explained the principle and mode of operation of my invention, and have illustrated and described a specific manner in which it may be practiced. However, I desire to have it understood that, within the scope of the appended claims, the invention may be practiced otherwise than as specifically described.

I claim as my invention:

1. The method of forming a blank for making a seamless tube, comprising progressively piercing a solid billet, and simultaneously expanding the diameter and reducing the wall thickness of the pierced portion of the billet while maintaining the cross sectional area of the major part of the

pierced portion of the billet substantially uniform during the expanding and reducing operation.

2. The method of forming a blank for making a seamless tube, comprising progressively piercing a solid billet, simultaneously expanding the diameter and reducing the wall thickness of the pierced portion of the billet, then expanding the diameter and reducing the wall thickness of the pierced billet, and during both of the expanding and reducing operations maintaining the cross sectional area of the billet substantially uniform.

3. The method of forming a blank for making a seamless tube, comprising piercing a solid billet, and subsequently expanding the diameter and reducing the wall thickness of the pierced billet while maintaining the cross sectional area of the pierced billet substantially uniform.

In testimony whereof, I sign my name.

RALPH C. STIEFEL.
